US00D883499S

(12) **United States Design Patent** (10) Patent No.: **US D883,499 S**
(45) Date of Patent: ** May 5, 2020

(54) **SMART GLOVE FOR REHABILITATION**

(71) Applicant: **NEOFECT CO., LTD.**, Gyeonggi-Do (KR)

(72) Inventor: **Byeong Geol Park**, Icheon-si (KR)

(73) Assignee: **NEOFECT CO., LTD.**, Yongin-si, Gyeonggi-do (KR)

(**) Term: **15 Years**

(21) Appl. No.: **35/506,397**

(22) Filed: **Sep. 7, 2018**

(80) **Hague Agreement Data**

Int. Filing Date: **Sep. 7, 2018**

Int. Reg. No.: **DM/102941**

Int. Reg. Date: **Sep. 7, 2018**

Int. Reg. Pub. Date: **Mar. 8, 2019**

(51) LOC (12) Cl. **24-02**

(52) U.S. Cl.

USPC **D24/190**

(58) **Field of Classification Search**

USPC D24/190, 188, 200

CPC A61F 5/013; A61H 1/0288
